His Attorney.

UNITED STATES PATENT OFFICE

CLIFFORD M. FOUST, OF SCHENECTADY, NEW YORK, ASSIGNOR TO GENERAL ELECTRIC COMPANY, A CORPORATION OF NEW YORK

SURGE-VOLTAGE RECORDER

Application filed August 6, 1926. Serial No. 127,710.

My invention relates to that class of apparatus employed to record electrical phenomena by means of the so-called Lichtenberg figures, which are most effectively produced by the exposure of a photo-sensitive film to electrical discharges. For a more complete description of the nature of such records, see the article "Klydonograph" by J. F. Peters, Electrical World, April 19, 1924.

10 Recording apparatus of this class has been used to determine the magnitude and character of electrical surges occurring on transmission systems. It is known that the figures produced by a positive surge or charge are larger and of a different character than those produced by a negative surge of the same magnitude. When the ordinary Lichtenberg camera is connected to a transmission line the half cycle of positive polarity 15 therefore determines the size of the spot or figure formed on the photo-sensitive film. Over-voltage surges of negative polarity will not appear until they are of such magnitude that they produce a negative figure 20 larger than the positive line voltage. It is desirable that all over-voltage surges be recorded regardless of their polarity and it is the primary object of my invention to provide recording apparatus for this 25 purpose.

In carrying my invention into effect, I provide apparatus which records all surges both positive and negative so that they appear as positive figures, yet so that those 30 which are produced by a negative surge are identified as such. In carrying my invention into effect I prefer to connect two recorders in parallel, but with reversed polarity between the transmission line and ground. If the surge is of positive polarity, it will be recorded by the recorder connected in the positive direction to the transmission line, and if it is of negative polarity 35 it will be recorded by the recorder of reverse polarity which is connected in the positive direction to ground. When a positive figure is being produced by one recording element, the corresponding negative figure is 40 also produced at the other recording ele-

ment, so that large positive and negative figures produced by exactly the same surge may be compared. If the surge is alternating in character, a positive figure will be produced by both recording elements simultaneously, but the positive and negative components of such a charge may be studied and compared directly by a comparison of the two positive figures.

Another feature of my invention which is applicable to recording apparatus generally is a novel way of photographing time characters directly upon the film.

The features of my invention which are believed to be novel and patentable will be pointed out in the claims appended hereto. For a better understanding of my invention, reference is made in the following description to the accompanying drawing in which Fig. 1 represents electrical connections for a preferred form of the apparatus; Fig. 2 shows a view, partially in section, of the recording apparatus; Fig. 3 represents a sectional view taken on line 3-3 of Fig. 2; Fig. 4 represents the nature 70 of the record produced by the apparatus; Fig. 5 is a detail view of the time recording element and Fig. 6 is an enlarged view of one of the time records.

Referring to Fig. 1, 10 represents a section of a transmission line to which the apparatus of my invention is connected to record surges occurring on said line. Any convenient connection may be employed to obtain a voltage for the recording apparatus which is proportional to the line voltage. In the present case I have shown the line connected to ground through a string of high tension insulators 11. This string of insulators will function as a condenser without allowing any appreciable flow of power between the line 10 and ground. The recording apparatus indicated at 12 is connected across a portion of this string and ground so that a voltage proportional to line voltage will be available for recording purposes. Preferably the connection will be made as near ground as possible, as at 13, so as to keep the recording apparatus near ground potential. 14 indicates an adjustable condenser connect-

ed between point 13 and ground to more exactly calibrate the voltage impressed upon the recorder. The essential parts of the recorder here shown comprise a drum 15 of insulating material having two internal conducting cylinders or electrodes 16 and 17 insulated from each other. A photo-sensitive film or recording element 18 is supported and moved by the drum on a portion of its exterior surface, and two bluntly pointed electrodes 19 and 20 rest lightly upon this film opposite to the two conducting cylinders 16 and 17. Electrode 19 is connected to the voltage tap 13 and the corresponding cylinder 16 is connected to ground, while electrode 20 is connected to ground and the corresponding cylinder 17 is connected to the voltage tap 13. Thus the drum is divided into two sections, one section 19, 16 for recording the positive surges, and the other section 20, 17 for recording the negative surges, both sections being arranged, due to the reversed polarity, to record such surges as positive figures. Similar electrical discharges simultaneously pass through the recording element in opposite directions. If it is desired that all voltage changes occurring on the transmission line be recorded, the switch indicated at 21 is kept closed. If it is desired to record only surges in excess of line voltage, the switch 21 is opened and the spark gap indicated at 22 is adjusted so that ordinary line voltages will not cause a discharge thereacross but so that voltages in excess of line voltages will.

The recording apparatus is preferably constructed in portable form as indicated in Figs. 2 and 3. The drum is rotatably mounted in a light tight box 25 and is driven by suitable clockwork or other timing motor indicated at 26 through appropriate gearing indicated at 27. The parts are electrically connected as shown in Fig. 1, the manner of making electrical connection to the rotating sections of the drum being indicated at 28. The photo-sensitive film is wound from a spool 29 about the drum onto a spool 30. The driving connection for the spools 29 and 30 being provided by elastic bands 31 and 32 which are stretched over the drum and spools outside of the film, as more clearly shown in Fig. 3. The type of drive automatically takes care of the varying diameter of the rolls 29 and 30. The film is kept tight by causing a slight friction on the shaft from which the film is unwound. An adjustable spring pressed against the end of the spool shaft, as indicated at 33, may be used for this purpose. The film is moved forward at a suitable rate—say one-half inch per hour—and the apparatus may contain enough film and be otherwise arranged to operate a week, for example, without attention, recording such phenomena as occur on the transmission line to which it is connect-

ed. Preferably, a timing wheel indicated at 34 is connected with the drum shaft through a friction clutch 35 and the film is timed by exposing the under side of the film in alignment with the electrodes 19 and 20 to a light emitting element through windows in a timing drum 37 driven with the timing wheel 34. The light ray emitting element shown at R in Fig. 5 may be a small amount of radium salt held in place on the end of an arm indicated at 36. A small lamp might also serve for this purpose. Preferably, the time is photographed on the film in the manner shown in Fig. 5. The holes 38 in the timing drum 37 are covered by a strip of transparent material such as tracing paper 39 forming windows, and over each hole the time character, indicated as "A" and "1", is printed on the tracing paper in bronze ink or some other material through which the rays do not readily pass. The shadow of the character is photographed. When the film is developed, we have an outline or shadow of the figure which remained unexposed in a circular exposed section of the film, as indicated in the enlarged section of the film in Fig. 6. The drum is preferably arranged to rotate once in 24 hours so that by providing twenty-four holes evenly spaced the hours are reproduced on the film. For 12:00 a. m. and 12:00 p. m., instead of the numbers, I print the characters "A" and "P" on the tracing paper, thereby distinguishing the a. m. and p. m. records so that the approximate time a surge record occurs is indicated directly.

When the film is developed the Lichtenberg figures indicative of the potential surges are of the character represented in Fig. 4. The left end of the record which has the continuous bands 40 indicative of the normal alternating current voltage of the line is produced with the switch 21, Fig. 1, closed. The right end of the record is produced by abnormal surges alone such as are large enough to jump the spark gap 22 with the switch 21 open. The upper record is produced by the positive electrode 19 and the lower record is produced by the negative electrode 20. Vertically aligned records are produced simultaneously by the same surge. Thus, figures 41 and 42 were produced by a positive surge of approximately 18 kilovolts; 41 is the positive figure and 42 the corresponding negative figure; 43 and 44 were produced by a negative surge of approximately $9\frac{1}{2}$ kilovolts; 45 and 46 is the record of a positive surge of $23\frac{1}{2}$ kilovolts superimposed upon the normal voltage record of the line which, in this case, was 3 kilovolts; 47 and 48 are similar records of a negative surge of approximately 13 kilovolts. It is seen that the negative surge record 47 is hardly distinguishable above the positive band record 40 produced by

normal voltage, although produced by a surge more than four times normal voltage. For this reason, it is desirable to record the positive component of this surge as at 48, 5 not only that the magnitude of the surge may be more accurately determined in accordance with the calibration of the instrument, but in order that the occurrence of the surge may become known at all.

10 The apparatus will be found useful for measuring or indicating the occurrence of various electrical phenomenon and is not limited to the use hereinbefore described.

In accordance with the provisions of the 15 patent statutes, I have described the principle of operation of my invention, together with the apparatus which I now consider to represent the best embodiment thereof, but I desire to have it understood that the 20 apparatus shown and described is only illustrative and that the invention may be carried out by other means.

What I claim as new and desire to secure by Letters Patent of the United States is:

25 1. Apparatus for recording figures indicative of the polarity and magnitude of voltages comprising two similar recording devices each comprising a sensitive recording element and electrodes for passing an electric discharge through such element and 30 parallel circuit connections associated with said electrodes for impressing voltages of equal magnitude but of opposite polarity upon said recording devices.

35 2. Recording apparatus comprising a drum of insulating material, a pair of cylindrical electrodes insulated from each other inside of the drum, a photo-sensitive record sheet supported on the exterior of said drum, 40 bluntly pointed electrodes resting lightly on the outer surface of said record sheet opposite to said cylindrical electrodes, and circuit connections for connecting said two sets of electrodes in parallel but in opposite 45 directions across a source of voltage.

50 3. The method of recording voltages by means of positive and negative Lichtenberg figures which consists in separating the voltage charge into two equal parts, and producing positive Lichtenberg figures with one part and negative Lichtenberg figures with the other part of said voltage charge.

In witness whereof I have hereunto set my hand this 5th day of August, 1926.

55 CLIFFORD M. FOUST.
